CLAIM

The ornamental design for a slicer housing as shown and described.

DESCRIPTION

FIG. 1 is a top, front-right perspective view of a first embodiment of a slicer housing;

FIG. 2 is a top, left-rear view thereof;

FIG. 3 is a top plan view thereof;

FIG. 4 is a rear elevation view thereof;

FIG. 5 is a front elevation view thereof;

FIG. 6 is a right-side elevation view thereof;

FIG. 7 is a left-side elevation view thereof;

FIG. 8 is a front-rear cross-section view thereof, taken along line 8-8 of FIG. 3, showing contours thereof; and

FIG. 9 is a front-rear cross-section view thereof, taken along line 9-9 of FIG. 3, showing contours thereof.

FIG. 10 is a top, front-right perspective view of a second embodiment of a slicer housing;

FIG. 11 is a top, left-rear view thereof;

FIG. 12 is a top plan view thereof;

FIG. 13 is a rear elevation view thereof;

FIG. 14 is a front elevation view thereof;

FIG. 15 is a right-side elevation view thereof; and

FIG. 16 is a left-side elevation view thereof;

FIG. 17 is a front-rear cross-section view thereof, taken along line 17-17 of FIG. 12, showing contours thereof; and, FIG. 18 is a front-rear cross-section view thereof, taken along line 18-18 of FIG. 12, showing contours thereof.

The dash-dash broken lines illustrate portions of the slicer housing, while the dash-dot-dash broken lines represent the bounds of the claim. The broken lines form no part of the claimed design. The bottom view is not shown, and no claim is made thereto.
